Primary Examiner — Steven J Czyz(74) *Attorney, Agent, or Firm* — Crowe & Dunlevy, P.C.(57) **CLAIM**

The ornamental design for a drop down gate latch, as shown and described.

DESCRIPTION

FIG. 1 is a perspective view of a drop down gate latch showing the design;

FIG. 2 is a front elevation view of FIG. 1;

FIG. 3 is a rear elevation view of FIG. 1;

FIG. 4 is a first side elevation view of FIG. 1;

FIG. 5 is a second side view of FIG. 1;

FIG. 6 is a top elevation view of FIG. 1; and,

FIG. 7 is a bottom elevation view of FIG. 1.

The broken lines shown in the figures represent portions of the article that form no part of the claimed design.

The drop down gate latch is shown with a symbolic break in its length. The appearance of any portion of the article between the break lines forms no part of the claimed design.

1 Claim, 7 Drawing Sheets(56)
